UNITED STATES PATENT OFFICE.

REX DE ORE McDILL, OF CIENFUEGOS, CUBA.

KEY RETAINER.

Application filed March 27, 1925. Serial No. 18,863.

To all whom it may concern:

Be it known that I, REX DE ORE McDILL, a citizen of the United States, residing at Cienfuegos, in the Province of Santa Clara and Republic of Cuba, have invented a new and useful Key Retainer, of which the following is a specification.

The object of my invention is to provide an improvement over the type of key retainers which have the keys suspended from one end; to provide a retainer which will permit free use of the keys and which will not permit the keys to fall off. It is also an object of my invention to provide a retainer in which the keys are concealed and in which the keys for one purpose may be segregated from those for other uses. I attain these and other objects of my invention by the device illustrated in the accompanying drawings, in which:—

Figure 1 is a front plan view of the key retainer in its open position;

Fig. 2 is a rear view of the back of the retainer in open position;

Fig. 3 is a view of the retainer in its normally closed position; and

Fig. 4 is a section on line 4—4 of Fig. 3.

Like characters of reference designate like parts in each of the following views.

Referring to the accompanying drawings, I provide a suitable collapsible folder comprising a back 1 and foldable flaps 2 and 3 integral with member 1, each of these flaps carrying the snap fastener 4. On one end of the back 1 I preferably provide a protecting plate 5 having a portion 6 of same folded over the edge of the back 1. I pro-

vide suitable eyeleted apertures 7 spaced at opposite sides of the back 1 through which a chain 8 passes. Chain 8 is required to be 40 of sufficient length to provide the loops 10 and 9 when the chain is in its normal position as shown in Fig. 1, on which loops keys, such as keys A and B may be strung. I provide a suitable spring ring 11 on chain 45 8 to permit of convenient removal or addition of keys whenever desired. Plate 5 is a metal plate and is preferably provided to protect the edge of the back 1 over which it is folded, as shown in Figs. 1 and 2, from 50 the friction of chain 8, the loop 9 of which is swung over the back of the flap 1, as shown. Different types of keys may, if desired, be placed on the loops of the chain 55 9 and 10 thus segregating one class of key from another class of key, while at the same time providing a flexible key retainer having ample room for enclosing a number of keys.

What I claim is:

In a key retainer, the combination of a 60 flexible folder comprising a back and foldable flaps, a snap fastener on the flaps, apertures in the back spaced apart from each other, a chain passing through the apertures and having one loop thereof inside the back 65 and another loop on the outside of the back, a chain of sufficient length to permit of the outside loop being swung over the edge of the folder and inside thereof, and a metal guard strip having a portion thereof over 70 the edge of the back on which the outside loop of the chain will rest when swung inside the folder.

REX DE ORE McDILL.
